ATTORNEY

UNITED STATES PATENT OFFICE.

GUSTAVUS A. LILLIENDAHL, OF GREENVILLE, ASSIGNOR TO HENRY T. LILLIENDAHL, OF JERSEY CITY, NEW JERSEY.

GAME APPARATUS.

SPECIFICATION forming part of Letters Patent No. 292,563, dated January 29, 1884.

Application filed July 24, 1883. (No model.)

To all whom it may concern:

Be it known that I, GUSTAVUS A. LILLIENDAHL, residing at Greenville, in the county of Hudson and State of New Jersey, have invented 5 a new and useful Improvement in Game Apparatus, of which the following is a specification.

My invention relates to a new and improved game designed for children or older persons; and it consists of one or more blocks having 10 a geometrical form, by preference that of the octahedron, and in providing these blocks with knobs or points projecting from the terminals or apices of the same, as is hereinafter set forth. These blocks may be molded or cast from 15 any suitable materials—such as any of the metals, or from celluloid or vulcanite—or may be wrought from wood, ivory, or bone.

The drawings represent, in Figure 1, my invention in the form of an octahedron, showing 20 a face view, and provided with points at the apices. Fig. 2 is a plan view of the same, and Fig. 3 is a face view, showing the block provided with knobs or spherically-shaped terminals.

25 I have represented the octahedral form in the drawings, but any of the geometrical forms may be used which may be adapted to this purpose—that is to say, having, by preference,

six or more sides or facets, upon which marks or numbers may be placed to indicate or identify such side or facet. In a game either one or any number of these blocks may be used, and the method of use is analogous to that of games now extant—that is, by throwing the blocks upon a table or other plane surface 30 and noting the particular number or figure upon the upper side or facet thereof. By the use of the points or knobs I am enabled to easily handle or grasp the blocks, and in this way the use of any special receptacle for 35 containing them is avoided. Another advantage is that the blocks in falling do not spread beyond a limited circle, and are certain to present one of the sides or facets uppermost.

Having thus described my invention, what I 40 claim therein as new, and desire to secure by Letters Patent, is—

Blocks having a geometric form, either plain or inscribed on the facets thereof, provided 45 with knobs or points at the apices, and adapted to be used as a game, substantially as set forth and shown.

GUSTAVUS A. LILLIENDAHL.
